UNITED STATES PATENT OFFICE.

ABRAHAM ROSENTHAL, OF ALTOONA, PENNSYLVANIA.

CLASP.

No. 857,488.

Specification of Letters Patent.

Patented June 18, 1907.

Application filed November 9, 1905. Serial No. 286,564.

To all whom it may concern:

Be it known that I, ABRAHAM ROSENTHAL, a citizen of the United States, residing at Altoona, in the county of Blair and State of 5 Pennsylvania, have invented new and useful Improvements in Clasps, of which the following is a specification.

My invention has relation to improvements in clasps designed especially for holding 10 small articles of wearing apparel such as gloves, stockings, and the like, and the invention consists in the construction and arrangement of parts, as will be hereinafter described and particularly pointed out in the 15 claim.

In the accompanying drawing: Figure 1 is a plan view of the blank from which the clasp is made and showing the same prior to bending in shape. Fig. 2 is a side elevation 20 of the clasp. Fig. 3 is a central longitudinal section taken on the line 3—3 of Fig 2.

Referring to the drawing, the numeral 1 designates the body of the clasp comprising a blank of resilient sheet metal bent into substantially 25 U-shaped form to provide two members, the opposite sides of which are approximately parallel with each other, providing a wide mouth or opening for the insertion of an article of wearing apparel, as seen in 30 Fig. 3.

Each member of the clasp is provided with oppositely disposed engaging portions or spring jaws 2 struck from the body of the blank approximately near its end and bent 35 toward each other to leave a space between their terminals. Said terminals are provided with teeth 3, said teeth being unbent and arranged in line with the body of the jaws. It will be readily seen that the clamping jaws 2 40 extend upwardly between the members of the clasp to or about the central portion which permits of an article being released from the teeth of the jaws by an upward pull on the article toward the bend of the members. By spacing the upper ends of the jaws 45

apart an article is readily slid upwardly between the same to engage said teeth whereby the article is suspended and supported thereby.

It will be readily seen in Fig. 1 that one of the jaws is provided with less teeth than the other jaw, so that the teeth on one jaw will point toward the spaces between the teeth of the other jaw. In practice gloves, neckties, and other small articles to be displayed 55 are inserted in the open ends of the members to a position between the clamping jaws 2, which have a sufficient amount of elasticity to permit of the article to pass upwardly between the same, the teeth serving to hold the 60 article securely without puncturing or injuring the same, owing to the peculiar arrangement of the teeth as hereinbefore described. The removal of the article is readily effected by sliding the same upwardly between the 65 members toward the U-bend.

Having thus described the invention, what I claim is:

A clasp for suspending and displaying articles of wearing apparel, comprising a flat strip of rectangular shaped resilient metal bent to U-shape, the sides being nearly parallel with each other and having rectangular shaped jaws struck approximately from near their ends, said jaws being provided with 75 teeth struck from their terminals, said jaws being bent inwardly toward each other and spaced apart at their upper ends so that the teeth on one jaw will point toward the spaces between the teeth on the other jaw, and said 80 jaws adapted to be sprung apart by an article interposed between the same to engage the teeth on said jaws, substantially as specified.

In testimony whereof, I affix my signature in presence of two witnesses.

ABRAHAM ROSENTHAL.
